LAMP BASE

John Sara, 5825 N. Rogers Ave., Chicago, Ill. 60646

Filed Jan. 17, 1973, Ser. No. 324,317

Term of patent 7 years

Int. Cl. D26—05

U.S. Cl. D48—20 R

FIG. 1 is a front elevational view of a lamp base showing my new design with the side opposite the one shown being identical to the side appearing herein;

FIG. 2 is a top plan view thereof;

FIG. 3 is a cross-sectional view taken through the line 3—3 of FIG. 1.

I claim:

The ornamental design for a lamp base, as shown.
